UNITED STATES PATENT OFFICE

156,712

GEM SETTING OR SIMILAR ARTICLE

Ferdinand Eichmuller, Jenkintown, Pa., assignor
to The Precious Metals Specialties Company,
Inc., Newark, N. J., a corporation of New Jersey

Application September 10, 1948, Serial No. 148,547

Term of patent 14 years

(Cl. D45—1)

To all whom it may concern:

Be it known that I, Ferdinand Eichmuller, a citizen of the United States of America, residing in the county of Montgomery and State of Pennsylvania, have invented a new, original, and ornamental Design for a Gem Setting or Similar Article, of which the following is a specification, reference being had to the accompanying drawings, forming a part thereof.

Fig. 1 is a top plan view of a gem setting, showing my new design;

Fig. 2 is a side elevational view thereof;

Fig. 3 is a vertical cross section through the center of the setting as shown in Fig. 1; and

Fig. 4 is a diagonal cross section across the corners of the setting as shown in Fig. 1.

I claim:

The ornamental design for a gem setting or similar article, substantially as shown.

FERDINAND EICHMULLER.
